DESIGN FOR A CHAIR

William Gerhard Carlson, Gardner, Mass., assignor to Hedstrom-Union Company, Gardner, Mass., a corporation of Massachusetts

Application February 17, 1937, Serial No. 67,721

Term of patent 3½ years

To all whom it may concern:

Be it known that I, William Gerhard Carlson, a citizen of the United States, residing in Gardner, in the county of Worcester and State of Massachusetts, have invented a new, original, and ornamental Design for a Chair, of which the following is a specification, reference being had to the accompanying drawing, forming part thereof.

Fig. 1 is a perspective front view of a chair showing my new design,

Fig. 2 is perspective rear view of the chair of Fig. 1,

Fig. 3 is a side elevation, and
Fig. 4 is a front elevation of the chair of Fig. 1.

I claim:

The ornamental design for a chair as shown.

WILLIAM GERHARD CARLSON.
